HYDROCARBON VAPOR LAMP OR BURNER

Frederick Charles Tilley, London, England

Application March 17, 1934, Serial No. 716,151
In Great Britain March 28, 1933

7 Claims. (Cl. 67—47)

This invention relates to hydro-carbon vapor lamps or burners, in which the fuel is forced up a vaporizing tube under pressure from a tank, the fuel being vaporized by heat as it passes through the vaporizing tube and when vaporized mixed with air in a mixing tube, the mixture passing down to a burner outlet or outlets surrounding the vaporizing tube to impinge on the inside of an annular bag-shaped mantle surrounding the vaporizing tube.

In such class of burner the air for mixing with the vapor has heretofore been introduced directly into the mixing tube. I have discovered this to be disadvantageous and it is therefore an object of this invention to provide an improved burner, whereby the air for mixing with the vapor is heated before it is combined with the vapor, and a more convenient construction of burner attained.

According to this invention, means are provided on the burner so constructed that the air for mixing with the vapor passes through the mantle, but not in contact with it, before it is mixed with the vapor, and such means may consist of an outer member encircling the vaporizing tube, formed or provided with an air passage or passages whereby the air enters the passage or passages and passes into an injector or mixing tube with the vapor from the vaporizing tube, the member being positioned below the burner outlet or outlets and preferably with a portion of its length within the mantle.

The invention will be clearly understood from the following description aided by the annexed drawing in which:

Figure 1 is a sectional elevation of a burner constructed according to one example of carrying the invention into effect.

Figure 2 is a section on the lines II, II of Figure 1, and

Figure 3 a section on the lines III, III, also of Figure 1.

Figure 4 is a sectional elevation of a modified construction of burner, and

Figure 5 a section on the lines V, V, of Figure 4.

The invention can be carried into effect in a variety of ways as to detail construction, and one example is shown in Figures 1, 2 and 3 of the accompanying drawing applied to a burner of the type in which the mantle encircles the vaporizing tube. In this case the vaporizing tube 1 is surrounded at part of its length (preferably within the area of the mantle) with a tubular member 2, having a series of passages 2a passing longitudinally through same, and a cen-

tral bore 2b, the central bore 2b being positioned on the vaporizing tube 1 with the passages 2a disposed around the vaporizing tube 1.

Above the top end of the vaporizing tube 1 and the tubular member 2, is an injector tube 3, and enclosing the injector tube 3 is a mixing tube or chamber, which may consist of a tube 4 having a dome shaped closed top, and such tube 4 leads to the burner outlets 5 within the mantle 6.

The injector tube 3 is preferably formed with a 10° conical bore 3a in a straight metal tube, the outlet end being rounded or curved as at 3b.

The various parts are detachably connected together by suitable joints and fittings such as by forming the burner ring 7, having the burner 15 outlets 5 with an internal screw thread 7a on the inside of the ring of outlets 5, and in one face of the ring 7 into which one end of the tubular member 2 formed with an external screw thread can be engaged, and on the other face of the ring 7 and within the circle of openings 5 is another internal screw thread 7b into which one screw-threaded end of a short tube 8 can be engaged, the other end of the tube 8 also being screw-threaded and to which a screw-threaded end of 25 the injector tube 3 can be connected by an internally threaded ring 9. The burner ring 7 is also formed with an internal screw-thread 7c outside the zone of outlets 5, into which a screw-threaded end of the mixing tube 4 can be engaged, or several of the parts may be made as one.

The mantle 6 is passed over the member 2 and burner ring 7, and the upper end engaged in a groove 17d, and the lower end around the member 2.

The whole of the burner can be positioned by telescoping the vaporizing tube 1 in central bore 2b and resting member 2 on a distancing tube 10 encircling the lower portion of the vaporizing tube 1.

The vaporizing tube 1 is connected to a pressure container 11 and is controlled by a valve 12, as is known.

In the modified example shown in Figures 4 and 5 of the accompanying drawing, the member 2 is formed with a hollow bore 2b and a series of longitudinal slots or recesses 2c in its periphery, and such member 2 is enclosed in an outer tube 13 covering the slots or recesses 2c, and so converting them into passages.

The tube 13 is longer than the member 2 and is preferably reduced in diameter below the member 2, but is of larger diameter than the vaporizing tube 1, leaving a passage 13a, the bottom end 55

being provided with air inlet holes 13b. The injector tube 3 may be of the same shape as that shown in Figure 1, or may be of inverted funnel shape as shown in Figure 4.

- 5 In use, the vaporizing tube 1 is heated in the usual manner, and the vapor passing upwards through the tube 1 into the injector tube 3 will suck air up through the passages 2a (Figure 1) or through the holes 13b, and passages 13a and 10 2c (Figure 4) passing as mixed vapor and air into the mixing tube 4, where the mixture is diverted downwards to the burner outlets 5, and so ensure a proper mixing, and as the air passes along the 15 passages 2a or 2c surrounding the vaporizing tube 1, it will be more efficiently heated by the burning mixture before mixing with the vapor as it issues from the vaporizing tube 1.

What I do claim as my invention and desire to obtain by Letters Patent is:—

20 1. In a hydrocarbon vapor device of the kind set forth, a mantle, a vaporizing tube extending through the mantle, a mixing chamber communicating with the mantle and into which said tube delivers fuel, conduit means providing a combustion air passage between the vaporizing tube and outer confines of the mantle in communication 25 with the atmosphere and the mixing chamber.

What I do claim as my invention and desire to obtain by Letters Patent is:—

- 20 1. In a hydrocarbon vapor device of the kind set forth, a mantle, a vaporizing tube extending through the mantle, a mixing chamber communicating with the mantle and into which said tube delivers fuel, conduit means providing a combustion air passage between the vaporizing tube and outer confines of the mantle in communication with the atmosphere and the mixing chamber.

25 2. In a hydrocarbon vapor device of the kind set forth, a mantle, a vaporizing tube extending through the mantle, a tubular device about said tube providing a passage between the vaporizing tube and outer confines of the mantle in communication with the atmosphere, and a mixing chamber means in communication with the mantle and into which said tube and passage respectively deliver fuel and air.

30 3. In a hydrocarbon vapor device of the kind set forth, a vaporizing tube, a member about said tube having a passage in communication with the atmosphere, a burner ring about said member, a mixing chamber into which said tube and passage respectively discharge fuel and air having one end closed and the other end open and connected to said ring, a mantle about said member and tube whereby the passage is disposed between the tube and outer confines of the mantle, and said ring having a passage establishing communication from said chamber to said mantle the position of the tubular member insuring heating of the air as well as the fuel before discharge into the mixing chamber.

35 4. In a hydrocarbon vapor device of the kind set forth, a vaporizing tube, means about said tube having a passage in communication with the atmosphere, a burner ring from which said means extends, an injector extending from the opposite side of the ring to the means into which said tube and passage respectively discharge fuel and air, a chamber member about the injector

closed at one end and connected at the other end to said ring, a mantle about said means whereby said passage is located between said tube and the outer confines of the mantle, and said ring having a passage establishing communication from said chamber to said mantle, the position of the first means insuring heating of the air as well as the fuel before discharge into the mixing chamber.

5. In a hydrocarbon vapor device of the kind 10
set forth, a vaporizing tube, means about said
tube having a passage in communication with the
atmosphere, a burner ring to which said means is
attached, an injector means attached to the op- 15
posite side of the ring to the first means and into
which said tube and passage respectively dis-
charge fuel and air, a dome-shaped mixing
chamber member disposed over said injector
means and connected to said ring, a mantle at- 20
tached to said ring and surrounding said first
means whereby said passage is located between
said tube and the outer confines of the mantle,
and said ring having a passage establishing com- 25
munication from said chamber to said mantle,
the position of the first means insuring heating
of the air as well as the fuel before discharge into
the mixing chamber.

6. In a hydrocarbon vapor device of the kind set forth, a vaporizing tube, a tubular member about said tube having longitudinal, exterior passages in communication with the atmosphere, an outer tube enclosing said passages, a burner ring to which said outer tube is attached, an injector attached to the opposite side of the ring to the outer tube and into which said vaporizing tube and passages respectively discharge fuel and air, a dome-shaped mixing chamber member disposed over said injector and connected to said ring, a mantle attached to said ring and surrounding said outer tube, and said ring having a passage establishing communication from said chamber to said mantle, the position of the device insuring heating of the air before discharge into the mixing chamber. 30 35 40

7. In a hydrocarbon vapor device of the kind 45 set forth a mantle, a vaporizing tube rising through the mantle, a mixing chamber adjacent the top of said vaporizing tube adapted to discharge downwardly into said mantle and into which said tube delivers fuel in an upward direction, 50 conduit means providing a combustion air passage between the vaporizing tube and the outer confines of the mantle in communication with the atmosphere at its lower end and in communication with the mixing chamber at its upper end, 55 the major portion of said passage being below the inlet zone of the fuel and air mixture into the mantle.
